UNITED STATES PATENT OFFICE

WADE E. SACKNER, OF GRAND RAPIDS, MICHIGAN, ASSIGNOR TO GRAND RAPIDS FIBRE CORD COMPANY, OF GRAND RAPIDS, MICHIGAN

MULTICOLORED PAPER CORD

Application filed May 18, 1931. Serial No. 538,073.

The object of this invention is to provide a paper cord of a strong texture and proper twist of variegated color similar to natural reed for chair bottoms.

5 Objects pertaining to details will appear from the description to follow.

A preferred embodiment of my invention is illustrated in the accompanying drawing, in which:

10 Fig. 1 is a plan view of a section of paper strip from which my improved cord is made.

Fig. 2 is a detail perspective view showing the method of folding the same longitudinally:

15 Fig. 3 is a detail view of a length of cord after it is twisted and finished.

Fig. 4 is an enlarged detail end view showing the disposition of the paper strip in the spun or twisted cord.

20 The parts will be identified by their numerals of reference.

1 is the paper strip, preferably of straw color, on which I distribute, by means described in a concurrent patent application,

25 Ser. No. 536,488, filed May 11, 1931, which has resulted in Pat. No. 1,886,428, a comparatively strong yellow stain at 2 separated into stripes to expose the straw colored paper to some extent, and a green stain 3 also disposed

30 in a pair of stripes towards the opposite margin of the paper strip. The paper strip here used is the product of the machine shown in said concurrent application. The colored stripes 2 and 3, as shown, are put on alternately by the felts of that machine as they strike the paper strip that is advanced at a constant rate of speed over the revolving felts. The result is that each felt applies to

35 the paper strip a series of spaced longitudinal colored stripes, such as 2, while the next succeeding felt places a series of different colored longitudinal strips spaced from one another and occurring on the paper between the strips of the first mentioned series of

40 stripes. The stripes of each series are substantially equal in length. This is done to simulate the appearance of the rush bottom of a chair or other piece of furniture when the cord is completed. In manufacturing

45 stripes. The stripes of each series are substantially equal in length. This is done to simulate the appearance of the rush bottom of a chair or other piece of furniture when the cord is completed. In manufacturing

50 with rushes, the weaver would select the

rushes of different colors to produce the desired effect of mingled colors in the chair seat. With automatically produced paper cord, it is necessary that the color be supplied to somewhat simulate the result obtained by the hand weaver, and it is necessary to supply the paper strip with comparatively evenly spaced stripes of color so that in the finished work, several stripes of one color will not lie side by side which would get away from the variegated effect desired in the seat. The felts of the machine described in my co-pending application run at constant speed so that this spacing and length of stripes is uniform. The stripes separate at the ends as shown in Fig. 1 so that when the cord is twisted, it gives the effect of two colored rushes twisted together. This is a very important item in simulating the natural seat and has been important in making possible the use of paper cord rather than the original rushes. The paper strip is cut three and five-sixteenths inches wide and is what is known as fifty pound basis paper. This is spun through a die six-thirty-seconds of an inch in diameter. The cord is twisted about seven turns to the foot and, while the cord thus has a round appearance, it is so twisted that it may be compressed nearly half the diameter at the turns around the seat frame when used for a chair bottom. This is necessary to make the proper spacing when using the cord in the making of chair bottoms in which the cords are woven around a frame and cross one another in the process of weaving in such a way that unless the cord could be compressed to half its diameter, there would be gaps between the cords.

The paper strip, which is of a quality and texture for the purpose, is folded upon itself longitudinally as it is spun into the cord with the long loose twist specified. The doubled edge of the paper gives strength and integrity to the cord and permits the long twist to be made use of and entirely encloses the plain side of the sheet, and presenting externally the variegated colors successively, producing a very pleasing effect closely imitating the appearance of freshly prepared flag or rush seats.

I am aware that paper cord has been twisted and made use of for this purpose prior to my present invention. I therefore desire to state that I wish to claim specifically the particular cord that I have here illustrated.

Having thus described my invention, what I claim as new and desire to secure by Letters Patent is:

- 10 1. An article of manufacture for use in making imitation rush furniture comprising a cord made up of a strip of paper having thereon a set of substantially equal length longitudinal stripes of one color at spaced regular intervals and having thereon a second set of substantially equal length longitudinal stripes of another color at spaced regular intervals, and having the stripes of one color disposed between the 20 strips of the other color, said strip being twisted to form a cord with a comparatively loose twist of about seven turns to the foot, the finished round cord being capable of compression to about one-half its diameter.
- 25 2. An article of manufacture for use in making imitation rush furniture comprising a cord made up of a strip of paper having thereon a set of longitudinal stripes of one color at spaced intervals and having thereon a second set of longitudinal stripes of another color at spaced intervals, and having the stripes of one color disposed between the stripes of the other color, said strip being twisted to form a cord with a comparatively loose twist of about seven turns to the foot, the finished round cord being capable of compression to about one-half its diameter.

In witness whereof I have hereunto set my
40 hand.

WADE E. SACKNER.
